BURNER CONTROL APPARATUS

Alfred F. Schumann, Baltimore, Md., assignor to
 Hauck Manufacturing Company, Brooklyn,
 N. Y., a corporation of New York

Application March 11, 1937, Serial No. 130,420

5 Claims. (Cl. 158—1)

The invention relates to mixer apparatus suitable for the intimate mixture of various fluids, particularly as fuels in a gaseous, liquid, and even powdered-solid state, for example, as in the mixing, or atomizing, of a combustible oil or gas or powdered fuel with air or steam or with a further combustible gas.

The invention has for an object the provision of mixer apparatus whereby, within the range of action of the mixer, a predetermined ratio may be maintained between two fluids supplied thereto, for example, in the case of burner apparatus to afford and maintain under variable output the desired atmosphere in a combustion chamber, thereby avoiding any danger of a change, say from an oxidizing to a reducing condition, or from an efficient to an inefficient flame.

A further object of the invention is to provide a burner apparatus and means for maintaining a predetermined pressure upon one of the fluids, with means admitting of the manual adjustment of the mixer apparatus in a manner whereby the selected ratio between the fluids is not changed throughout the range of variation of the total supply or output; also to permit of a change in the initial supply of the one fluid to alter the characteristic of the discharge.

Still another object of the invention is to afford a system of control which will admit of ready adjustment of the range of output of such burner apparatus, as well as the particular output at which the adjusted range of operation shall commence.

In carrying out the invention, for example as embodied in burner apparatus, there is combined with a suitable burner member having an adjustable discharge opening and means for varying the effective area thereof in a manner to afford a predetermined flow characteristic of the discharge of one fluid therethrough, a valve for supplying fuel to the discharge means, said valve being of a nature to afford a similar flow characteristic.

Provision is made, also, for manually establishing the desired port area ratio between the valve and the burner discharge openings, and to insure the maintenance of a constant pressure upon the fluids to be mixed, as in securing ample capacity in the medium supplying mains to substantially the point of use. Regulating means for two separate fluids are so controlled that a predetermined ratio between the fluids is constantly maintained throughout the range of operation of the apparatus, the range also being readily adjustable; and the combination permits, also, of

initially setting the flow of one of the fluids to afford the desired volume thereof, as by varying its supply pressure.

The nature of the invention, however, will best be understood when described in connection with the accompanying drawings, in which:

Fig. 1 is an end elevation of the novel apparatus with a portion of the fuel-supplying valve broken away.

Fig. 2 is a plan view thereof with a portion of the burner member broken away.

Referring to the drawings, the burner member is shown to consist of a suitable elongated casing or body having a longitudinally disposed chamber 10 into which the atomizing gaseous medium, 15 as air under requisite pressure, is to be supplied. The casing is provided with a removable tip 11 having the delivery outlet 12 located axially with respect to the casing.

Fitting coaxially within the body is the fuel supply nozzle 13 which extends from the rear of the casing to the outlet end thereof, terminating in a head 14 provided with circularly disposed radial outlets 15, the nozzle being bored axially to afford communication to these outlets and designed to connect, for example, through a pipe 16 or the like with a fuel supply valve 17 which may be rigidly attached to the burner casing, as by a bracket 18.

Intermediate the casing and nozzle member 30 and axially adjustable therein is a sleeve 20 having peripheral openings 21 to admit air from the interior of the casing to the interior of said sleeve and about the nozzle outlets 15, the sleeve extending beyond said outlets and being provided with an outlet 22 for mixed fuel and air. The said sleeve outlet 22 flares toward the delivery outlet 12 of the casing and terminates in juxtaposition thereto. The inner surface of this sleeve provides a constricted annular portion or throat 23 affording a secondary orifice about the neck of the nozzle, the surface immediately in advance of and succeeding said constricted portion flaring in opposite directions. The design of the orifice, together with a further air orifice hereinafter described, is such that a predetermined flow characteristic, for example a straight line flow characteristic, will be attained in the delivery of the gaseous medium.

The periphery of the said sleeve, furthermore, 50 is separated from the casing and forms with the delivery end thereof a tapering annular or primary orifice 24 contracting toward the outlet 12, which orifice may be varied in cross-sectional area in accordance with axial adjustment of the 55

said sleeve, which, to this end, has a sliding fit through the rear portion of the casing and about the inner end of the nozzle member. Provision is made for axially displacing the sleeve as 5 through the angular movement of an arm 25 extending from a collar 26 which is connected to the end of said sleeve, opposite its outlet, through a pin 27 operating in a helical slot 28 formed in an extension of the casing, the head 10 of said pin passing into a slot 29 formed in the collar 26. Therefore, by angularly moving the said collar through the arm 25, the sleeve 20 will be correspondingly reciprocated toward and away from the outlet 12.

15 The advance and retraction of the sleeve is to occur simultaneously with variation in the fuel supplied to the burner, as from the valve 17. This valve may consist of any suitable fuel-metering valve having a predetermined flow 20 characteristic such as a straight line flow characteristic and conforming to the flow characteristic of the burner. There is attached to the valve stem 40 of the valve an arm 41 angularly movable, as hereinafter set forth, to adjust the 25 port area of the valve for regulating the rate of fuel supply by said valve to the burner member. Moreover, in the fuel supply pipe 42 from which the fuel is supplied to the valve from a suitable source (not shown), there is introduced means 30 for maintaining a predetermined pressure of the fuel supplied. Thus, there may be included in the pipe-line 42 a pressure-reducing valve 43 embodying an adjustable tensioning means such as the spring 44 for setting the valve to supply 35 the fuel at the desired pressure, which pressure may be adjusted by means of an externally projecting stud 45 extending within the valve body and bearing upon said spring.

As hereinbefore noted, the invention contemplates the simultaneous operation of both of the control means for the burner and valve, respectively, and in a manner such that uniform angular movement will be imparted to their respective arms 25 and 41 to maintain thereby a predetermined ratio between the atomizing medium supplied to the burner and the fuel supplied thereto. Thus, the two said arms are linked together at like distances from their respective axes of oscillation as by means of a link 50; and provision is 50 made for moving this link longitudinally as, for example, from a shaft 51 having suitable operating means such as a handle 52 for rocking the same. This shaft, through intermediate mechanism including a crank 53 secured to the shaft and a block 54 adjustable on the crank and secured to the free end of a rod 55, imparts a suitable throw to the said rod whose other end is adjustably secured in a block 56 swivelled to the link 50 connecting the arms 25 and 41.

In order to change the throw of crank 53, the same is provided with a slot 57 in which is fitted a pin 58 extending laterally from the head 54. By sliding this pin along the slot and adjusting the rod 55 in block 56, and then securing said rod to the block in the adjusted position as by means of a set screw 59, the desired range of operation will be determined. Moreover, it will be appreciated that the particular point at which such operation is initiated may also be adjusted by first setting the link 50 through sliding of block 56 along rod 55. This will position the respective arms 25 and 41 of the burner and valve to secure the particular openings desired, whereupon, by 70 locking the block 56 to rod 55, the output of atom-

ized mixture may be varied through operation of the handle 52, as hereinbefore set forth.

By this expedient, not only may the mixer apparatus for the two fluids be operated to vary the total supply or output from any particular point, while maintaining constant the ratio between the fluids, but the initial supply of the one fluid may be set as desired to alter the characteristic of the discharge. Moreover, the actual range of control may be regulated as by the adjustment of the throw of the crank, as hereinbefore set forth.

I claim:

1. Apparatus of the nature set forth, comprising in combination a fixed tubular discharge element for fluid, having connection with a source of air and provided with an axial outlet, a movable sleeve mounted coaxially within the discharge element, its one end affording with the outlet an annular discharge area, means connected with the sleeve to adjust the same longitudinally for changing the effective discharge area, a valve provided with a port communicating with the discharge element and with a source of fluid fuel supply, means to adjust the effective port area, means in advance of said valve for maintaining constant a predetermined pressure on the fuel supplied to the valve, and means connecting said two adjusting means to each other for imparting simultaneously thereto movement of like angular amount to change in the same sense the respective areas and the discharge of both fuel and air through the said outlet of the discharge element.

2. Apparatus of the nature set forth, comprising in combination a fixed tubular discharge element for fluid, having connection with a source of air and provided with an axial outlet, a movable sleeve mounted coaxially within the discharge element, its one end affording with the outlet an annular discharge area, angularly movable means connected with the sleeve to adjust the same longitudinally for changing the effective discharge area, a valve provided with a port communicating with the discharge element and with a source of fuel supply, angularly movable means to adjust the effective port area, means in advance of said valve for maintaining constant a predetermined pressure on the fuel supplied to the valve, and means connecting said two adjusting means to each other at equal distances from their respective axes of oscillation and including a movable element for imparting simultaneously thereto a like angular movement to change in the same sense the respective areas and the discharge of both fuel and air through the outlet of the discharge element.

3. Apparatus according to claim 2 and characterized by the provision of means for adjusting manually the effective port area independently of movement of the connecting means.

4. Apparatus according to claim 2 characterized by the provision of means for limiting the extent of angular movement of said connecting means.

5. Apparatus of the nature set forth, comprising in combination a fixed tubular discharge element for fluid, having connection with a source of air and provided with an axial outlet, a movable sleeve mounted coaxially within the discharge element, its one end affording with the outlet an annular discharge area, an angularly movable arm and intermediate mechanism connecting the same to the sleeve for adjusting the latter to change the effective discharge area, a

valve provided with a port communicating with the discharge element and with a source of fuel supply, an angularly movable arm connected with the valve to adjust its effective port area, means in advance of said valve for maintaining constant a predetermined pressure on the fuel supplied to the valve, a longitudinally adjustable rod connecting said arms to each other at equal distances from their respective axes of oscillation, and a crank for imparting simultaneously to both arms a throw to maintain a predetermined ratio between the fuel and air discharged through the outlet of the discharge element, together with means for setting the throw of the crank.

ALFRED F. SCHUMANN.
